SURGICAL INSTRUMENT

Bertrand O. Frezieres, Colorado Springs, Colo.

Application September 8, 1936, Serial No. 99,757

2 Claims. (Cl. 27—23)

My invention relates to instruments for use in autopsies and my object is to provide a simple and cheaply manufactured instrument for holding the head of a body being operated upon. 5 Other objects will appear as the description progresses.

Figure 1 is a view showing the instrument in position with respect to the head being operated upon.

10 Although I show the preferred embodiment of my invention I do not thereby limit myself to the precise form shown, but wish it understood that within the scope of what hereinafter is claimed, various changes in the precise shape 15 and other details of construction may be made without departing from the spirit of the invention.

The device comprises a yoke 1; a thumb screw 2 provided with a point 3 and mounted in each 20 end portion of said yoke; a shank 4 extending from the yoke 1; and a handle provided with a pair of grips 5.

In use the yoke 1 is placed about a head H and the points 3 of the thumb screws 2 are set 25 into the bone only firmly enough to prevent slipping, as shown in Figure 1.

With this instrument the operating surgeon or an assistant can hold the head H firmly in the proper position while the skull is being sawed.

30 When the back side of the head H is being sawed,

the instrument is turned up forward on the pivotal points 3 of the thumb screws 2. When the front side of the head H is being sawed, the instrument is turned down backward. In any and all positions, the instrument allows free 5 access to the saw and the operator, and holds the head H with a non-slipping hold.

What I claim as new is:

1. A surgical instrument for use in autopsies, comprising a yoke; and a pointed thumb screw 10 mounted in each end portion of said yoke so that both thumb screws have a common axis; said yoke being adapted to be disposed about the skull to be operated upon, and said thumb screws being adapted to be set into said skull 15 directly above the ears so as to provide facilities for turning and holding said skull in any desired angle while said skull is being sawed.

2. A surgical instrument for use in autopsies, comprising a yoke provided with a shank; and 20 a pointed thumb screw mounted in each end portion of said yoke, said thumb screws being disposed substantially concentrically; said yoke being adapted to be disposed about the skull to be operated upon and said thumb screws being 25 adapted to be set into said skull directly above the ears so as to permit said yoke to be swung out of the way of the surgeon's saw.
